UNITED STATES PATENT OFFICE

ROY R. TURNER, OF HOUSTON, TEXAS

DESIGN FOR A BROOM HANDLE

Application filed October 18, 1930. Serial No. 37,308. Term of patent 3½ years.

To all whom it may concern:

Be it known that I, Roy R. TURNER, a citizen of the United States, and residing at Houston, in the county of Harris and State of Texas, have invented a new, original, and ornamental Design for Broom Handles, of which the following is a specification, reference being had to the accompanying drawing, forming a part thereof.

Fig. 1 is a side elevation of a broom handle

showing my new design; Fig. 2 is a cross sectional view thereof.

The design is continued throughout the handle, the appearance of the opposite side being substantially the same as that shown in Fig. 1.

What I claim is:

The ornamental design for a broom handle as shown and described.

ROY R. TURNER.
